ADJUSTABLE RAIL BRACE

Albert F. Huber, Chicago, and Charles E. Godfrey, Batavia, Ill., assignors to American Brake Shoe Company, New York, N. Y., a corporation of Delaware

Application May 17, 1946, Serial No. 670,553

7 Claims. (Cl. 238—293)

1

The invention relates to adjustable rail braces commonly used for bracing the rail at railway switches and other places subject to thrust.

One type of rail brace, which has gone into extensive use, comprises a stationary wedge block and a movable wedge block connected by a bolt and nut member. Tightening of the bolt acts to tighten the wedge. Such braces give satisfactory service in that they positively hold the stock rail in its seat against the side thrust of traffic. They are also usually easily and accurately adjusted for wear. When the rail creeps in the direction tending to loosen the wedge, the bolt is usually strong enough to prevent shifting of the wedge blocks and the assembly either acts as an anti-creeper or the stock rail slips by the brace. However, these braces are objectionable in that longitudinal creepage action of the stock rail in the other direction often tightens the wedge, thus permitting the bolt to become loose.

Among the principal objects of the invention is to provide such a rail brace which is inexpensive to build, simple to install and adjust, effective in operation, and capable of retaining its adjustment regardless of direction of forces caused by track creepage action.

The invention also consists in certain new and original features and combinations hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which:

Fig. 1 represents a side elevation of the brace in position;

Fig. 2 is a plan of the brace in position with parts broken away, taken on line 2—2 of Fig. 1;

Figs. 3 and 4 are vertical sections taken on the lines 3—3 and 4—4 of Fig. 1.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings, the brace is shown in position against a stock rail 12 resting on a switch slide plate 11 which in turn rests on

2

a conventional railway tie 10. The slide plate 11 (which, broadly speaking, may also be termed a tie plate) has a recessed seat providing a shoulder 16 against which the flange 15 of the rail abuts, and a second shoulder 17 against which the rail brace abuts. The brace is shown used in connection with a switch, the movable switch point 18 being indicated in closed position disposed against rail head 13. The switch point 18 slides on slide plate 11 to open the switch as will be understood by those skilled in the art.

The adjustable rail brace comprises in general two backers or blocks 19 and 20 welded to the tie plate 11 and constituting in effect a stationary wedge element or block; a movable wedge element or block 23 abutting the rail 12, and a bolt 24 and nut 25 for adjusting the brace.

The stationary block member 19 has an enlarged, substantially longitudinally extending opening 21 connecting with a slot 26, and the stationary block member 20 has an enlarged opening 28, these aligned openings accommodating the L-bolt 24, as explained hereinafter. The stationary wedge block 19, 20 has a wall portion 29, 30 having a vertical wedging surface supported by a base portion indicated in general by 31 disposed against plate shoulder 17.

The movable wedge block 23 has a vertical wedging surface 33 cooperating with wedge walls 29, 30 and also a toe portion 34 disposed under the wedge walls 29, 30. The movable wedge block 23 has a side and bottom surface fitting respectively the web 14 and base 15 of the rail, and a clearance space 36 between upper and lower rail contacting portions. The movable block 23 does not engage the rail head 13.

The movable wedge block 23 has a transversely extending opening 37 in which the head 39 of bolt 24 snugly fits. Bolt 24 also has a threaded shank 38 loosely passing through holes 27 and 28. The stationary wedge block members 19 and 20 are so spaced as to snugly accommodate an adjusting nut 25 threaded on shank 38.

The stationary wedge blocks 19, 20 are secured to the tie plate 11 by fillet welds located at the transverse sides of both block members, as indicated at 42, 43 and 44, 45. These blocks are also integrally secured to tie plate 11 by J-welds 46, 47, the corners of the blocks being cut away to form recesses to accommodate these welds.

In use, the stationary wedge block members 19, 20 are applied to the tie plate 11 as indicated; the L-bolt is placed in the movable wedge block hole 37; and the movable wedge block 23 and L-bolt 24 are placed in position with the nut 25 disposed between the stationary wedge blocks to receive the L-bolt 24. The nut 25 is then turned by a suitable track wrench until the movable wedge block 23 is tightly wedged into position.

against the stock rail 12. The position illustrated is a typical normal position when the brace is first installed and tightened.

It will be noted that the slot 26 provides ample space for accommodating the head 39 of the L-bolt to permit the wedge to be tightened to take up any wear which occurs during use. The wedging surfaces of the blocks tightly force the movable block against the stock rail 12 and the toe 34 engaging under the wedge portions 29 and 30 acts to hold down the movable block and, through it, the base flange of the stock rail. Although the shank 38 of the L-bolt fits loosely in the stationary wedge member holes 27 and 28, there is a tight fit between bolt head 39 and movable block hole 37 and between the nut 25 and the stationary block members 19 and 20 on either side. These tight-fitting parts insure holding the movable wedge block 23 in proper relationship to the stationary wedge block 19, 20, regardless of any longitudinal movement of the stock rail 12 in either direction tending to either loosen or tighten the movable block 23.

Thus an adjustable rail brace is provided which overcomes the disadvantages of prior braces of this type while retaining the advantages of such prior type. It is easily and accurately adjusted for wear and prevents shifting of the movable block in either direction caused by creepage of the stock rail due to expansion or contraction, or movement of traffic, or other reason.

While certain novel features of the invention have been disclosed herein, and are pointed out in the annexed claims, it will be understood that various omissions, substitutions and changes may be made by those skilled in the art without departing from the spirit of the invention.

What is claimed is:

1. In an adjustable rail brace, a wedge element adapted to be secured to a tie plate or the like, said wedge element having a wedge surface, a substantially longitudinally-extending bolt opening and an intermediate recess; a rail-contacting member having a wedge surface engaging said first wedge surface and a transverse opening; an L-bolt having a head fitting said transverse opening and a shank loosely fitting said bolt opening, and a nut on said shank engageable with the opposite walls of said recess.

2. In an adjustable rail brace, a wedge element adapted to be secured to a tie plate or the like, said wedge element having a wedge surface, a substantially longitudinally-extending bolt hole, a slot extending from said bolt hole to said wedge surface, and an intermediate recess intersecting said bolt hole; a rail-contacting member having a wedge surface engaging said first wedge surface and a transverse opening; an L-bolt having a head snugly fitting said transverse opening and a shank loosely fitting said bolt hole, and a nut on said shank located between the opposite walls of said recess.

3. In a rail brace, a stationary wedge block comprising spaced wedge members adapted to be secured to a tie plate or the like, said stationary wedge members having a wedge surface and aligned openings, an L-bolt having a threaded shank disposed in said aligned openings, a nut between said wedge members and threaded on said shank, a movable wedge block having a wedge surface engaging said first wedge surface, a rail-contacting surface adapted to engage the rail, and an opening in which the L-shaped head of said bolt is disposed.

4. In a rail brace construction, a tie plate having a recessed seat with opposed shoulders, a

rail in said seat against one of said shoulders, a stationary wedge block comprising spaced wedge members seated in said seat against said other shoulder, said stationary wedge members having vertical wedge surfaces, aligned openings, and lower shoulders, an L-bolt having a threaded shank disposed in said aligned openings, a nut between said wedge members and threaded on said shank, a movable wedge block having a vertical wedge surface engaging said first wedge surfaces, a rail contacting surface engaging the base flange and web but not the head of said rail, and having an opening in which the L-shaped head of said bolt is disposed; said movable block having a horizontally extending toe disposed under said lower shoulders, the lower inner longitudinal edge of said stationary wedge members having recesses, welding securing the transverse edges of said stationary block members to said tie plate, and welding in said recess securing said wedge members to said tie plate.

5. An adjustable rail brace comprising a wedge element having a wedge surface and adapted to be secured to a tie plate or the like, a movable wedge element having a wedge surface cooperating with said first wedge surface and having a portion engaging the rail, a bolt member and a nut member thereon for drawing said wedge elements into tightening engagement, said bolt member having a part non-rotatably and longitudinally locked to one of said wedge elements, said other wedge element having spaced abutments between which said nut member acts to provide rotatable interlocking engagement therewith, whereby to prevent relative movement between said wedge elements in both directions lengthwise of the rail.

6. In an adjustable rail brace, a wedge element adapted to be secured to a tie plate or the like, said wedge element having a wedge surface, a substantially longitudinally-extending bolt hole, and an intermediate recess intersecting said bolt hole; a rail-contacting member having a wedge surface engaging said first wedge surface, a bolt member having a shank loosely fitting said bolt hole, a nut member on said shank for exerting thrust against the opposite walls of said recess, and a transversely extending member connecting said bolt member and said rail-contacting member.

7. In an adjustable rail brace, a wedge element adapted to be secured to a tie plate or the like, said wedge element having a wedge surface, a substantially longitudinally-extending bolt hole, a slot extending from said bolt hole to said wedge surface, and an intermediate recess intersecting said bolt hole; a rail-contacting member having a wedge surface engaging said first wedge surface, a bolt member having a shank loosely fitting said bolt hole, a nut member on said shank for exerting thrust against the opposite walls of said recess, and a transversely extending member connecting said bolt member and said rail-contacting member and disposable in said slot.
